UNITED STATES PATENT OFFICE.

ARTHUR J. BOYNTON, OF LORAIN, OHIO.

GAS-BURNER.

1,061,811.

Specification of Letters Patent.

Patented May 13, 1913.

Application filed May 2, 1912. Serial No. 694,724.

To all whom it may concern:

Be it known that I, ARTHUR J. BOYNTON, a citizen of the United States, residing at Lorain, in the county of Lorain and State 5 of Ohio, have invented a new and useful Gas-Burner, of which the following is a specification.

My invention relates to the construction of gas burners for blast furnace gases which 10 are used on hot blast stoves, for firing boilers, and in firing kilns and similar apparatus.

One object of my invention is to provide a gas burner of improved construction having 15 novel means whereby regulation and control of the supply of gas and air is effected, and proper mixing thereof is attained.

Another object of the invention is to provide 20 a gas burner having improved operating means whereby the gas burner is moved into and out of operative position and is held in operative position, and further objects of the invention will be more fully 25 described and claimed hereinafter.

Referring to the accompanying drawings forming part of this specification, Figure 1 is a sectional elevation showing a gas burner constructed and arranged in accordance with 30 my invention as applied for use on a hot blast stove. Fig. 2 is a transverse section on the line II—II Fig. 1, showing a detail of the gas and air conveyer and the grid or damper by which the supply of air mixed 35 with the gases is regulated and controlled.

Fig. 3 is a sectional end elevation of the gas burner and the branch pipe or conduit through which gas is supplied to the burner, taken on the line III—III of Fig. 1.

40 In the drawings 2 designates a horizontally extending tubular gas conduit which is rotatably mounted in the vertical branch pipe 3 by which the gas conduit 2 is connected to the gas box 4. An opening 5 in the side wall of the conduit 2 adjacent to its closed rear end connects the interior 45 of the conduit 2 with the branch pipe 3.

The plate 6 removably secured on the outer end of the conduit, by engaging with the 50 branch pipe 3, prevents lengthwise movement of the conduit 2 relative to the branch pipe. The upper end of the branch pipe 3 is provided with a cap 7 to secure the conduit 2 in place thereon and the flanged lower 55 end of the pipe 3 is bolted to the flanged outlet 8 on the gas box 4. The gas box 4

is connected in the usual manner with a branch pipe (not shown) leading from a gas main, gas flue, or other source of gas supply, and its construction not forming a 60 part of this invention, the gas box 4 will not be further described.

The closed rear end of the gas conduit 2 is provided with a flanged branch 9, and a lever 10 on the branch 9 provides a convenient means for turning or rotating the tubular gas conduit 2 in the supporting pipe 3 so as to vary the size of the opening 5 connecting the conduit 2 and branch pipe 3 in regulating and controlling the amount 65 of gas supplied to the conduit 2. A pipe or tube 11 is secured by one end in the opening 12 in the branch 9 on the rear end of the conduit 2 to provide a supply of air to the center of the gas conduit 2 at its 70 forward or discharge end, a current of air being induced in this pipe by the inflowing gases.

Mounted in front of the conduit 2 on the base plate 13 is a support 14 having parallel 80 ways 15 on the top surface thereof forming a track for the wheels 16 with which the gas and air conveyer 17 forming part of my improved gas burner is provided so as to be movable relative to the conduit 2 and 85 movable into and out of position with respect to the gas inlet 18 on the hot blast stove 19 or other device to which the gas burner is applied for use. A stop 20 is provided on the track support 14 and a pawl 90 21 pivoted on the shaft or axle 22 for the track wheels 16 is arranged to swing and bring its outer end into engagement with the stop and hold the nozzle 23 in its extended position when the burner is in use. 95 The hand wheel 37 on one end of one axle 22 affords means for moving the pawl 21 on this axle 22 into and out of engagement with the stop 20. Lugs or ears 24 on the nozzle 23 and on the lower section of the split 100 branch pipe 25 are employed to form bearings for the axles 22.

The gas and air conveyer forming part of my improved apparatus comprises a central frame having a series of horizontally 105 extending transverse slots or openings 26 therethrough forming gas passages which connect the chamber 27 formed by the split branch pipe 25 surrounding the discharge end of the conduit 2 with the nozzle 23 110 secured on the opposite side of the gas and air conveyer frame. The branch pipe 25

preferably is split lengthwise into sections, as shown, to facilitate the assembling of the apparatus. Between the horizontal openings 26 in the mixer frame are transverse slots or openings 28 which open at each end through the sides 29—29 of the frame of the gas and air conveyer and which also open on the front side 30 into the nozzle 23 of the gas and air conveyer.

10 Mounted on opposite sides of the gas and air conveyer so as to be vertically movable, are grids 31 having a series of slots 32 therein arranged to register with the slots or openings 28 which are adjustably held in place by means of an adjusting screw 33 having a hand wheel 34 on one end thereof. The screw 33 extends through the cross arm 35 by which the upper ends of the grids 31 are connected and held in position against the sides of the gas and air conveyer frame and its lower end bears on the top of the mixer frame so that by turning the hand wheel 34 the grids 31 will be raised or lowered to move the slots 32 relative to the openings and vary the size of the air inlet openings leading into the gas and air conveyer frame. A cross arm 36 is also employed to connect the lower ends of the grids 31 and maintain the grids in alinement.

30 The gas and air conveyer and its nozzle 23 is pushed or moved manually on the track rails 15 into and out of position in front of the gas inlet 18 on the stove 19. The branch pipe 25, (as will be seen in Fig. 1) telescopes on and moves horizontally relative to the conduit 2, the gas and air conveyer and its nozzle 23 moving with the branch pipe 25 on the support 14.

40 The operation of my improved gas burner is as follows: When applied to a hot blast stove the door 38 closing the gas inlet 18 to the stove, when the stove is "on air", is unfastened and is moved away from in front of the gas inlet 18, as shown, the door being suspended by an arm 39 having wheels 40 on its upper end from the track 41 secured on the side of the stove. The burner is then moved forwardly manually on the supporting ways 15 to bring the nozzle 23 in position in front of the gas inlet 18 on the stove. The hand wheel 37 on one shaft 22 for the track wheel 16 is then turned to move the pawl 21 into engagement with the stop 20 to hold the nozzle 23 of the burner 50 in position in proximity to the gas inlet 18 on the stove. The gas rises from the gas box 4 upwardly through the branch pipe 3 into the conduit 2 and passes out of the forward end of the conduit into the chamber 27 connecting the gas burner with the gas and air conveyer. The gas then passes through the series of parallel openings 26 in the gas and air conveyer into the nozzle 23 of the gas and air conveyer, where the gas is 60 mixed with the entering air. Air is drawn

through the openings in the opposite sides 29 of the gas and air conveyer into the series of parallel air inlets 28 which are arranged to alternate with the gas openings 26 in the gas and air conveyer and passes from the inlets 28 into the nozzle 23 of the gas and air conveyer where it is thoroughly mixed with the gas. The mixture of gas and air then passes from the nozzle 23 into the gas inlet opening 18 in the stove where it becomes ignited and is burned. The grids 31 on the sides of the gas and air conveyer are moved relatively to the gas and air conveyer by means of the hand wheel 34 to regulate the volume of air admitted into the gas and air conveyer and the hand lever 10 on the closed end of the conduit 2 is moved to rotate the conduit in the pipe 3 forming the support therefor so as to vary the size of the gas inlet opening 5 into the conduit 2 from the supporting pipe 3. The gas is permitted to burn as long as desired and when it is intended to shut off the gas, the hand lever 10 is rotated so as to move the opening 5 leading into the tubular conduit 2 until this opening is opposite and is closed by the cap 7 on the pipe 3 when the gas will be shut off. The hand wheel 37 on the axle 22 for the track wheels is then manipulated to lift the pawl 21 out of engagement with the stop 20, and the nozzle 23 of the gas burner is moved backwardly until again in the position shown in the drawings. The door 38 is then moved until it is again in front of the gas inlet 18 on the stove 19, in which position it is bolted or otherwise secured.

65 The advantages of my invention will be apparent to those skilled in the art. The apparatus is simple and is easily kept in repair. By its use the mixture of air and gases is readily changed as is found necessary or desirable and the gas burner is quickly moved into and out of position in front of the stove or other device to which it is applied for use.

70 Modifications in the construction and arrangement of the parts may be made without departing from my invention. Although the apparatus is shown applied for use to a hot blast stove it is also adapted for use in furnaces of boilers and kilns and with various other devices.

75 I claim:—

1. A gas burner comprising a conduit, a support in which said conduit is rotatably mounted through which gas is supplied thereto, a gas and air conveyer in front of and movable relatively to said conduit, means on the conveyer telescoping on the end of and connecting the conduit with said conveyer, said conveyer having gas inlets from the conduit and having independent air inlet openings.

80 2. A gas burner comprising a tubular con-

- duit, a support in which said conduit is rotatably mounted through which gas is supplied to the conduit, a gas and air conveyer in front of and movable relatively to said 5 conduit, means on the conveyer telescoping over the end of and connecting the conduit with said conveyer, said conveyer having gas inlets from the conduit and independent air inlet openings, and means adjustably secured 10 on the conveyer to vary the size of said air inlets and regulate the air supply thereto.
3. A gas burner comprising a conduit, a support in which said conduit is rotatably mounted through which gas is supplied to 15 the conduit, a gas and air conveyer in front of the conduit, and movable with respect thereto, means on the conveyer telescoping on the end of and connecting the conduit with said conveyer, a nozzle for the conveyer, said conveyer having gas inlets connecting the conduit with the nozzle, independent air inlets opening into said nozzle, and a support on which said conveyer and nozzle are movably mounted. 20
- 25 4. A gas burner comprising a conduit, a support in which said conduit is rotatably mounted through which gas is supplied to the conduit, a gas and air conveyer in front of the conduit, and movable with respect thereto, means on the conveyer telescoping on the end of and connecting the conduit with said conveyer, a nozzle for the conveyer, gas inlets on the conveyer connecting the conduit with the nozzle, independent air 30 inlets opening into said nozzle, a support on which said conveyer and nozzle are movably mounted, and fastening means on the conveyer and support for securing said conveyer against backward movement on the support when the conveyer is in extended 35 position.
5. In a gas burner a gas and air conveyer, a series of inlets extending from side to side therethrough for supplying gas thereto, a series of air inlet openings therein, and a grid on said conveyer adjustably secured thereon to regulate the supply of air to the conveyer. 45
6. In a gas burner, a gas and air conveyer comprising a rectangular frame having a plurality of parallel gas passages with inlet 50
- and outlet openings in two opposite sides thereof, a series of air passages having inlet openings in the other two sides thereof, and outlet openings in the same side as the 55 outlet openings for the gas passages, and means on the inlets to the air passages for varying the size thereof and regulating the air passing therethrough.
7. In a gas burner, a gas and air conveyer 60 comprising a rectangular frame having a plurality of parallel gas passages with inlet and outlet openings in two opposite sides thereof, a series of air passages having inlet openings in the other two sides thereof, and 65 outlet openings in the same side as the outlet openings for the gas passages, sliding grids having openings registering with the inlet openings to the air passages, and means for moving the grids to regulate and control the 70 supply of air to said air passages.
8. In a gas burner a gas and air conveyer comprising a frame having a plurality of parallel gas passages and a plurality of air passages alternating with said gas passages, 75 sliding grids arranged to register with the inlets to the air passages, and means for moving the grids to regulate and control the supply of air to said air passages.
9. A gas burner comprising a conduit, a support in which said conduit is rotatably mounted through which gas is supplied to the conduit, a gas and air conveyer in front of the conduit, and movable with respect thereto, means on the conveyer telescoping 80 on the end of and connecting the conduit with said conveyer, a nozzle for the conveyer, gas inlets on the conveyer connecting the conduit with the nozzle, independent air inlets opening into said nozzle, a support 85 on which said conveyer and nozzle are movably mounted, and a pawl and stop co-acting to fasten and secure the conveyer and nozzle thereon against backward movement on the support when the nozzle is in extended 90 position on said support. 95

In testimony whereof, I have hereunto set my hand.

ARTHUR J. BOYNTON.
